PUMP FOR LUBRICANTS AND THE LIKE

Spicer D. Shearman, Bryan, Ohio, assignor to The Aro Equipment Corporation, Bryan, Ohio, a corporation of Ohio

Application May 23, 1945, Serial No. 595,419

6 Claims. (Cl. 103—5)

1

My present invention relates to a pump for lubricant and the like having a novel primer piston and pump plunger arrangement.

One object of the invention is to provide a simple structure having means to both prime a pressure pump and at the same time operate the pressure pump by means of a single reciprocating motion of a pump rod.

Another object is to provide an arrangement wherein a primer piston is reciprocable in a cylinder and in the cylinder a pump plunger is arranged, the primer piston having a cylinder to cooperate therewith to pump lubricant at high pressure from the pump structure and to create a vacuum on the return stroke which quickly sucks the lubricant brought to the high pressure pump by the primer piston into the cylinder of the high pressure pump when it leaves the plunger.

Another object is to provide an arrangement of this character in which the piston rod is hollow so that the lubricant under high pressure may pass up through it to the discharge port of the pump.

A further object is to provide a simple arrangement which involves few parts and but little assembly labor for fabricating a pump structure including a means to prime the pump.

With these and other objects in view, my invention consists in the construction, arrangement and combination of the various parts of my device whereby the objects contemplated are attained, as hereinafter more fully set forth, pointed out in my claims and illustrated in the accompanying drawing, wherein:

Fig. 1 is a vertical, sectional view through a pump for lubricant and the like embodying my invention, and showing the primer piston in lowered position;

Fig. 2 is an enlarged sectional view of the pump mechanism per se showing the primer piston in elevated position; and

Fig. 3 is a bottom plan view of Fig. 2.

On the accompanying drawing I have used the reference numeral 10 to indicate a tubular container having a bottom 12. A lid 14 is provided for the container 10 and it may be secured to the container as by means of clamp screws 16 and 18 coacting with brackets 20 and 22 on the tank and brackets 24 and 26 on the lid. The clamp screw 16 has a wing nut 28 and the clamp screw 18 has a sleeve nut 30 threaded thereon, as illustrated.

A pump head 32 is mounted on the lid 14 as by

bolts 34 and has a tubular housing 36 depending therefrom into the container 10. An extension tube 38 is also provided which serves as a primer cylinder and it is coupled to the tube 36 by a nipple 40.

Within the primer cylinder 38 a piston 42 of cup leather type is reciprocable. It is supported by the lower end of a high pressure cylinder 44 which has a head 46. The head 46 contains an outlet valve seat 48 against which a check valve 50 of ball type is adapted to normally seat.

The head 46 is connected at its upper end with a tubular rod 52 which is threaded into the lower end of a piston rod 54. The piston rod 54 has a bore 56 part way into it from the lower end, and this bore communicates by means of a side outlet 58 with a cavity 60 in the head 32. The cavity 60 communicates with an outlet port 62 which extends to the point of use such as the usual grease hose ending in a discharge nozzle, which may or may not be the valved type, as desired.

A packing gland 64 surrounds the piston rod 54 for retaining packing 66 in the lower end of the head 32 to avoid leakage between the head and the piston rod. The tube 36 has breather openings 68, the purpose of which will hereinafter appear.

For reciprocating the piston rod 54 I provide a hand lever 70 pivoted to the head 32 by means of a link 72. The lever 70 carries a pivot pin 74 with which the upper end of the rod 54 is connected after extending out of the head through a packing nut 76.

The high pressure cylinder 44 is adapted to coat at times with a high pressure plunger 78 which has a shouldered down portion 80 supported in a hub 82. The hub 82 is connected by spokes 84 with an annular member 86. The member 86 is connected with the lower end of the plunger cylinder 38 by means of a connector ring 88 having its upper and lower ends flanged over as shown in Fig. 2. The shouldered down portion 80 is retained in the hub 82 by a nut 90.

Freely slideable on the tubular housing 36 and in the cylinder 38 is a hub 92 and a cone-shaped follower plate 94. The plate 94 is adapted to follow the lubricant 96 in the container 10 and has a peripheral flange 98 extending upwardly. The flange 98 occupies a position close enough to the wall of the container 10 to clean the lubricant from the wall with the exception of a thin film.

Practical operation

In the operation of my pump structure, the

cylinder 44 and the plunger 78 together constitute a high pressure pump, whereas the piston 42 and the cylinder 38 constitute a primer therefor. Beginning with the lower end of the stroke, as in Fig. 1, it will be obvious that there is no pumping action within the cylinder 44 when the direction of reciprocation is reversed and the cylinder 44 is moved upwardly. The check valve 50 will close from the position of Fig. 1 to the position of Fig. 2 as soon as such movement is started, and the plunger will accordingly produce a vacuum within the cylinder 44. At the same time, the upward movement of the piston 42 draws lubricant in through the ring 86 between the spokes 84 thereof for charging the space within the cylinder 38 surrounding the plunger 78 when the lower end of the piston 42 leaves the upper end of the plunger 78. The vacuum in the cylinder 44 will at that time draw a charge of lubricant up into the cylinder.

Upon the down stroke this charge of lubricant will be trapped in the cylinder 44 by the plunger 78, and will be displaced therefrom through the check valve 50 and into the tubular piston rod 52. The lubricant passing through the check valve 50 will displace any lubricant above it upwardly through the bore 56 of the piston rod 54, then outwardly through its port 58 into the cavity 60, and from there through the discharge opening 62 into the lubricant hose.

From the foregoing description it will be obvious that I have provided an element 44-42 which serves both as a high pressure cylinder and a primer piston. When this element is reciprocated, it primes the high pressure pump and by cooperation of its cylinder with the plunger 78, the lubricant is dispensed at a pressure depending upon the area of the plunger 78 in relation to the pressure on the handle 70. The high pressure pump is effectively and efficiently primed each time the cylinder 44 leaves the upper end of the plunger 78, thus eliminating all voids in the stream of lubricant being dispensed.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a pump for lubricant and the like, a primer cylinder, a primer piston movable therein, a pump cylinder carried by said primer piston, a pump plunger carried by said primer cylinder, said pump cylinder being movable onto and off of said pump plunger, said primer cylinder and pump cylinder communicating freely with each other when the pump cylinder is off the pump plunger, an outlet check valve carried by said pump cylinder, and a tubular piston rod con-

nected therewith for operating said primer piston and pump cylinder and for receiving the lubricant from said check valve and discharging it to a discharge port of the pump.

5 2. In a pump for lubricant and the like, a primer cylinder, a primer piston movable therein, a pump cylinder carried by said primer piston, a pump plunger carried by said primer cylinder, said pump cylinder being movable onto and off of said pump plunger, said primer cylinder and pump cylinder communicating freely with each other when the pump cylinder is off the pump plunger, and an outlet check valve carried by said pump cylinder.

10 3. In a pump of the character disclosed, a primer cylinder, a primer piston movable therein, a stationary pump plunger, a pump cylinder simultaneously movable with said primer piston and being movable onto and off of said pump

20 plunger, said primer cylinder and pump cylinder communicating freely with each other when the pump cylinder is off the pump plunger, and a tubular piston rod connected with said pump cylinder for operating it and said primer piston and for receiving the lubricant therefrom and discharging it from the pump.

25 4. In a pump structure, a cylinder, a primer piston reciprocable therein, a plunger carried by said cylinder, said piston having a cylinder co-

30 operable with said plunger to pump fluid, a piston rod for reciprocating said primer piston and said pump cylinder, to provide suction and discharge strokes, said cylinders being in free communication with each other at the end of a suction stroke, and an outlet check valve carried by said pump cylinder.

35 5. In a pump structure, a cylinder, a piston reciprocable therein, a plunger carried by said cylinder, said piston being hollow to receive said

40 plunger and cooperate therewith to pump fluid, a piston rod for reciprocating said piston and said pump cylinder, to provide suction and discharge strokes, said cylinder and the hollow portion of said piston being in free communication with each other at the end of a suction stroke, and an outlet check valve carried by said pump cylinder, said piston rod being hollow and the outlet side of said check valve communicating therewith.

45 6. In a pump structure, a cylinder, a primer piston reciprocable therein, a spider at the lower end of said cylinder, a plunger carried by said spider, said piston having a bore cooperable with said plunger to pump fluid, a piston rod for reciprocating said primer piston, to provide suction and discharge strokes, said cylinder and said bore being in free communication with each other at the end of a suction stroke, and an outlet check valve carried by said primer piston and communicating with said bore.

SPICER D. SHEARMAN.
